UNITED STATES PATENT OFFICE

108,268

DESIGN FOR AN AIRPLANE

Arthur E. Raymond, Santa Monica, and Edward F. Burton, Los Angeles, Calif., assignors to Douglas Aircraft Company, Inc., Santa Monica, Calif., a corporation of Delaware

Application January 15, 1937, Serial No. 67,079

Term of patent 7 years

To all whom it may concern:

Be it known that we, Arthur E. Raymond and Edward F. Burton, citizens of the United States, the former residing at Santa Monica, in the county of Los Angeles and State of California, and the latter residing at Los Angeles, in the county of Los Angeles and State of California, have invented a new, original, and ornamental Design for an Airplane, of which the following is a specification, reference being had to the accompanying drawings, forming part thereof.

Fig. 1 is a plan view;

Fig. 2 is a front elevational view;

Fig. 3 is a side elevational view; and

Fig. 4 is a perspective view of the airplane of our design, this view particularly illustrating the empennage and its relation to the tail portion of the fuselage.

The characteristic feature of the design resides in the empennage and its association or emergence with the fuselage.

We claim:

The ornamental design for an airplane substantially as shown and described.

ARTHUR E. RAYMOND.
EDWARD F. BURTON.
